AUTOMATIC TAMPER FOR RAILROAD TRACKS

Filed July 1, 1948

Fig. 1.

Fig. 2.

This cross-sectional diagram illustrates a heat exchanger assembly. The central vertical structure is labeled 70. On the left, a vertical tube assembly 60 is shown, with a horizontal tube 72 extending from its top. The right side features a vertical tube assembly 40, with a horizontal tube 72 extending from its top. A horizontal tube 42 connects the top of the left tube assembly 60 to the top of the right tube assembly 40. The top of the right tube assembly 40 is connected to a vertical tube 30, which is further connected to a horizontal tube 44. The bottom of the left tube assembly 60 is connected to a vertical tube 90, which is further connected to a horizontal tube 50. The bottom of the right tube assembly 40 is connected to a vertical tube 90, which is further connected to a horizontal tube 50. The diagram also shows a central vertical tube 72 positioned between the two main tube assemblies.

AUTOMATIC TAMPER FOR RAILROAD TRACKS

Bernard M. McCallum, Council Bluffs, Iowa

Application July 1, 1948, Serial No. 36,390

6 Claims. (Cl. 104—10)

1

This invention relates to the problem of maintaining ballast under railway track ties and more particularly to an improved device for tamping ballast under a tie automatically and in response to the travel of trains across the tie.

In the past, it has been the practice to employ laborers with tamper bars to replace the ballast under ties after it has been vibrated out of position. This is a costly and inefficient process.

As a result attempts have been made to employ the vibration of the rails to ballast back under the tie. These attempts have been unsuccessful largely because the tampers employed merely pack a hole into the ballast alongside a tie, then reciprocate back and forth in the hole without further tamping.

This has been the case because the ballast around the hole thus formed becomes hard and does not jiggle downwardly to fill the bottom of the hole to provide more gravel to be tamped.

It is therefore an object of this invention to provide an automatic tamper for railroad tracks which is so constructed as to loosen gravel on its upward vibration stroke, permitting gravel to fall into the path of the tamper for packing on its downward vibration stroke.

Another object of the invention is to provide a tamper as described, which is provided with tamping surfaces slanting outwardly from and downwardly from a railroad tie for compacting dirt under the tie in a more efficient manner than heretofore.

Still a further object of the invention is to provide a railroad tamper having tamping surfaces disposed beneath the railroad tie for more efficient tamping action.

Yet another and further object of the invention is to provide a tamper as described employing a plurality of tamping portions or protrusions extending outwardly from the tamper and alongside a railroad tie in use, such portions being spaced apart for permitting gravel loosened by the portions to fall therebetween downwardly toward the bottom of the tie.

Another object of the invention is to provide a device for the purpose described which is sturdy and durable in construction, reliable and efficient in operation, and relatively simple and inexpensive to manufacture, assemble and utilize.

Other and still further objects and advantages of the invention will become apparent from the following detailed description of a preferred embodiment thereof.

2

In the drawings:

Figure 1 is a side elevation of the tamper of this invention, shown as attached to an end portion of a rail, an end portion of an adjacent rail also being shown, the two rails being connected together by a joint bar, a portion of which is broken away, a railroad tie to be tamped being shown in cross-section.

Figure 2 is a view, generally similar to Figure 10 1 in all respects with the exception that Figure 2 is taken in looking at the tamper from the other side or inside of the rail;

Figure 3 is a view-in-section taken along the line 3—3 of Figure 2; and

15 Figure 4 is a perspective view of the tamper of the invention, portions of the securing bolt thereof being broken away.

The tie tamper of this invention is generally indicated at 10 in Figure 1 and is shown as attached about a railway tie 12 and to a railway rail, generally indicated at 14.

The rail 14 is provided with a foot or flange 16, a web 18 and a ball or head 20. The rail 14 is disposed closely spaced apart from an adjacent rail 22, the two rails being connected together by means of two joint bars 24.

25 The joint bars 24 generally have three holes therethrough for the purpose of receiving three bolts 28, which are disposed in use extending through the bars 24 on one side of the rail, through the web 18, and through the joint bars 24 on the opposite side of the rail.

30 The joint bars 24 are preferably of an approximate L-shape having an obtuse angle between the main body portion 32 of the bar and a leg portion 34 of the bar. The leg 34 is provided with a lower end inclinedly disposed with respect to the main body portion 32 of the bar for engagement with a portion 41 connecting the tops of two spaced apart foot receiving portions 40 of the tamper 10.

35 The lock 30 is preferably of an approximate L-shape having an obtuse angle between the main body portion 32 of the lock and a leg portion 34 of the lock. The leg 34 is provided with a lower end inclinedly disposed with respect to the main body portion 32 of the lock for engagement with a portion 41 connecting the tops of two spaced apart foot receiving portions 40 of the tamper 10.

40 The foot receiving portions 40 are spaced apart longitudinally of the rail and are disposed on the same side of the rail. The under surface of the lock 30 is preferably inclined in parallelism with the adjacent upper surface of the foot 16.

45 The connecting portion 41 is disposed in use closely spaced apart from the web 18 and beneath the lock 30.

50 The distance between the under surface of the lower end of the lock 30 and the bolt 28, together with the thickness of the connecting portion 41,

55 The distance between the under surface of the lower end of the lock 30 and the bolt 28, together with the thickness of the connecting portion 41,

is such that the lock 30 will bear downwardly upon and clamp the portion 41 against the foot 16 at times when the bolt 28 is tightened.

The tamper 10 further includes two second foot receiving portions 42 which may also be described as second sections of the foot receiving portions 40. The second foot receiving portion 42 are of an approximate V-shape, as is the portion 40. The portions 42 receive the other side of the foot 16.

The open ends of the V-shaped portions 40 and 42 are disposed toward each other and the said portions are of sizes and shapes for close disposal about the respective opposite sides of the foot 16.

The foot portion 42 is provided with two upwardly extending flange portions 44 which latter are adapted to be disposed in parallelism with the web 18 at a time when the foot receiving portion 42 is disposed closely adjacent to and receiving the foot portion 16.

The upright flange portions 44 are each provided with apertures therethrough for receiving the end bolts 28, the said apertures being disposed at the bolts 28 at times when the foot receiving portions 42 are disposed about the foot 16.

The flanges 44 are interconnected at their upper ends by a second flange connecting member 46 which latter extends between the two and in parallelism with the rail 14 in use.

Beneath each of the foot receiving portions 40 and 42 one of two tamping arms or portions are provided, each having an inclined under surface 52 which slants downwardly and toward the tie 12.

The tamping surfaces 52 are preferably disposed entirely lower than the under surface of the tie 12 and the ends 54 of the tamping portions 50 preferably extend beneath the tie 12, past the respective side surfaces of the tie 12. The under surfaces 52 are preferably convexly curved.

The upper sides of the tamping portions 50 are preferably concavely curved generally in parallelism with the under surfaces 52.

The tamping portions or shoes 50 preferably extend longitudinally of the tie 12 a certain distance limited by the cost of manufacturing the tampers.

The under surfaces 52 of the tampers 50 are each provided with a lug 60 extending outwardly therefrom and transversely thereto. The under surfaces of the lugs 60 preferably extend downwardly and to the side from the tie 12.

The lugs 60 preferably extend in horizontal rows from side to side and substantially co-extensive of the tamping portions 50.

The tamping portions 50 are each held in place by one of two spaced apart frameworks or frames 70, which includes two pairs of parallel spaced apart upright standards which interconnect the foot receiving portions 40 and 42 at each side of the device with the respective tamping portions 50.

A plurality of cross members 72 are also included in the framework 70. The cross members 72 are transversely disposed in use with respect to the rail 14 and are spaced apart from each other. The purpose of the cross bars 72 is to support thereon a plurality of lugs or protrusions 80. The lugs or fingers 80 are spaced apart from each other in directions transverse to the rail 14 and are disposed in rows vertically spaced apart. The tamping portions or lugs 80 are connected at one end to the outer side of their respective cross members 72.

The under surfaces of each of the lugs 80 ex-

tend downwardly and away from the tie 12 at a slant for pushing ballast downwardly and toward the tie 12 during downward vibrational movements of the lugs 80.

Beneath the several horizontal rows of the lugs 80 on each side of the tamper 10 one or more vertically spaced apart and parallel angle bars or angle bar portions 90 are provided. The angle bars 90 extend between and are secured to the upright framework standards and are horizontally disposed in use. The under surfaces of the angle bars 90 are slanted downwardly and outwardly from the tie 12 in use.

In operation, it will be seen that the tamper 10 of this invention is attached to the end of a rail 14 in the manner described and that as trains pass over the rail the tamper will define upward and downward vibrational movements.

On each upward movement the upper lugs or tamping portions 50 will tend to loosen the adjacent ballast permitting the latter to fall downwardly between the lugs 80 on the outer side of the framework standards, and also permitting some of the ballast to fall between the lugs 80, between the cross members 72 and downwardly between the standards of the frames 70 and the adjacent tie 12.

The ballast will be engaged by the angle bars 90 and the lugs 60 and the slanted under surfaces of the angle bars 90 and lugs 60 will cause the ballast to be packed downwardly and inwardly toward the bottom of the tie 12. When the ballast has reached the underside of the tie 12, it is further packed under the tie by the blunt ends 54 of the tamping portions 50.

It will be seen that on an upward vibrational stroke less ballast is carried upwardly than is carried downwardly on a downward stroke. This is true because of the downward inclination of upper sides of the lugs 80, angle bars 90 and the bottom lugs 60.

It will be seen that this invention has provided an automatic tie tamper, which is particularly adapted for efficient operation because it loosens the ballast on an upward stroke for providing ballast beneath its tamping surfaces to be tamped on the downward stroke. This invention also provides a more reliable and efficient tamping device than heretofore.

From the foregoing description, it is thought to be obvious that an automatic tamper for railroad tracks constructed in accordance with my invention is particularly well adapted for use by reason of the convenience with which it may be assembled and operated, and it will also be obvious that my invention is susceptible of some change and modification without departing from the principles and spirit thereof and for this reason, I do not wish to be understood as limiting myself to the precise arrangement and formation of the several parts herein shown in carrying out my invention in practice, except as claimed.

I claim:

1. A device for attachment to a railway track at the point where the ends of two rails are abutted, the track having a tie disposed beneath the end of one of said rails, said device comprising: a ballast-tamping member, said member having a section thereof extending downwardly from said rail on one side of or below said tie, said section having at least one tamping surface downwardly disposed, and said section being provided with a plurality of ballast-loosening protruding portions disposed above said tamping

surfaces, said protruding portions being elongated and being disposed extending outwardly from said section on the side thereof opposite said tie, said protrusions having slanted under surfaces, said under surfaces being disposed extending downwardly and outwardly from the remainder of said section, said protrusions being provided with slanted upper surfaces, said upper surfaces being disposed extending downwardly and outwardly from the remainder of said section.

2. A device for attachment to a railway track at the point where the ends of two rails are abutted, the track having a tie disposed beneath the end of one of said rails, and at least one joint bar being disposed alongside said rail, said bar being provided with a plurality of apertures therethrough disposed in registry with the apertures in said rail, said rails being substantially of an I-shape in cross-section and each having a foot portion normally downwardly disposed transversely of a center portion, said rails each being provided with a plurality of longitudinally spaced apart apertures through its center portion at said abutted end, said device comprising: a ballast-tamping member, said member provided with downwardly sloping fingers on the outer surface and having a section thereof extending downwardly from said rail on one side of and below said tie, the upper end of said section being provided with an aperture disposed in alignment with said rail aperture and with said bar aperture; and a bolt disposed through the aperture in said section and through an aperture in said bar and through an aperture in said rail for securing all rigidly together.

3. A device for attachment to a railway track at the point where the ends of two rails are abutted, the track having a tie disposed beneath the end of one of said rails, said device comprising: a ballast-tamping member having an elongated frame portion adapted for extending downwardly from said rail on one side of and below said tie the lower end of said ballast tamping member having an arcuate shoe thereon extended under the said tie; a plurality of ballast-loosening protruding portions disposed extending transversely outwardly of the frame on one side thereof and below; and means for securing said ballast-tamping members to said rail.

4. A device for attachment to a railway track at the point where the ends of two rails are abutted, the track having a tie disposed beneath the end of one of said rails, said device compris-

ing: a ballast-tamping member, said member having a section thereof extending downwardly from said rail on one side of and below said tie the lower end of said ballast tamping member having an arcuate shoe thereon extended under the said tie, said section having at least one tamping bar attached thereto and extending outwardly from said section on the side thereof opposite said tie, said tamping bar having a downwardly disposed tamping under surface, said tamping bar having an upper surface slanting downwardly and outwardly from said tie, and said section being provided with a plurality of ballast-loosening protruding portions disposed above said tamping surfaces, said protruding portions being elongated and being disposed extending outwardly from said section on the side thereof opposite said tie.

5. In a rail actuated tamper, the combination which comprises a railroad rail, a tie upon which the rail is positioned, a pair of frames having outwardly and downwardly sloping fingers extended from the outer surfaces thereof positioned below the rail and spaced from the sides of the tie, said frames having arcuate shoes on the lower ends extended below and inwardly under the tie, and means mounting the said frames on the rail.

6. In a rail actuated tamper, the combination which comprises a railroad rail, a tie upon which the rail is positioned, a pair of frames having spaced vertically disposed side bars connected at the upper ends with bars extended longitudinally of the rail and said side bars connected by cross bars extended transversely of the rail and positioned below the rail, said side bars having arcuate shoes on the lower ends extended below and under the said tie, outwardly and downwardly sloping fingers on the cross bars of the upper parts thereof and outwardly and downwardly sloping plates on the cross bars of the lower parts thereof, and means mounting said frames on the rail.
